UNITED STATES PATENT OFFICE.

GEORGE S. HILL, OF STRAFFORD, NEW HAMPSHIRE, ASSIGNOR, BY MESNE ASSIGNMENTS, TO UNITED SHOE MACHINERY CORPORATION, OF PATERSON, NEW JERSEY, A CORPORATION OF NEW JERSEY.

TAKE-UP MECHANISM.

1,361,057.

Specification of Letters Patent.

Patented Dec. 7, 1920.

Application filed October 21, 1916. Serial No. 126,923.

To all whom it may concern:

Be it known that I, GEORGE S. HILL, a citizen of the United States, residing at Strafford, in the county of Strafford and 5 State of New Hampshire, have invented certain new and useful Improvements in Take-Up Mechanism; and I do hereby declare the following to be a full, clear, and exact description of the invention, such as will enable others skilled in the art to which it 10 appertains to make and use the same.

The invention relates to buttonhole sewing machines, and more particularly to take-up mechanism for such machines.

15 The object of the invention is to provide a novel and improved rotary take-up or thread-controlling mechanism which is well adapted for use in machines in which the sewing mechanism is rotated in sewing 20 about the end or ends of the buttonhole, and which will act smoothly and efficiently when operated at high speed.

To this end the invention comprises the 25 features of construction and combination of parts hereinafter described and referred to in the claims.

The various features of the invention will 30 be readily understood from an inspection of the accompanying drawings, and the following detailed description of the mechanism illustrated therein.

In the drawings Figure 1 is a sectional elevation showing so much of a buttonhole sewing machine as is necessary to illustrate 35 the application of the present invention thereto; and Fig. 2 is a detail front elevation showing the upper needle and take-up mechanism.

In the drawings the invention is shown 40 as embodied in a buttonhole sewing machine having the same general construction and mode of operation as the machine shown and described in application Serial No. 104,449, filed June 19, 1916.

45 The machine comprises, in general, a cutter which operates to cut the buttonhole slit after the completion of the sewing, a reciprocating and laterally-moving work clamp, and a sewing mechanism which is rotated 50 during the sewing about the eye of the buttonhole, and which comprises a vertically-reciprocating and laterally-vibrating or jogging upper needle, and looping and loop-spreading devices including a thread-carrying looper arranged below the work and co-

operating with the laterally-vibrating needle to form the well-known Humphrey stitch.

In the machine shown the work clamps indicated at 2 are mounted upon work-supporting plates 4 which are pivoted on a longitudinally and laterally moving clamp carriage 6. The clamps are automatically closed prior to the beginning of the sewing, and are automatically opened at the completion of the buttonhole, by mechanism which 60 forms no part of the present invention and which need not be described. The buttonhole slit is cut at the completion of the sewing by a cutter operated by a cam on the main cam shaft of the machine. The work 65 is carried by the clamps over a throat plate 10 mounted upon a turret 12, which carries the under looping and loop-spreading mechanism.

The upper needle 14 of the sewing mechanism is eccentrically mounted in a hollow needle bar 16. The mechanism for vibrating or jogging the needle bar comprises a vertically-reciprocating and laterally-vibrating carrier sleeve 18, within which the 70 needle bar reciprocates. The carrier sleeve is reciprocated vertically through a bell-crank lever 20, the horizontal arm of which is connected by a ball joint with the upper end of the sleeve, and the vertical arm of 75 which is connected by a link 22 with an eccentric on the sewing shaft 24. The lower end of the sleeve is moved laterally by a link 26, one end of which is connected with a pivot 28 on a rotary head 30. When the 80 sleeve is moved downward the link acts to swing the lower end of the sleeve and the needle bar toward the right so that the 85 needle bar will be positioned for the depth stitch. When the sleeve is raised the link 90 acts to swing the sleeve toward the left so that the needle bar will be positioned to form the slit or edge stitch. The needle bar is reciprocated by a crank 32 which is secured to the front end of the needle shaft 100

34 and is connected to the needle bar by a link 36. The needle shaft is geared to make two revolutions for each revolution of the sewing shaft, and the needle carrier will therefore be moved to the right during one 105 reciprocation of the needle and to the left during the succeeding reciprocation, so that the needle will vibrate or jog so as to alternately form the depth and edge stitches.

The rotary head 30, in which the carrier 110

- sleeve and needle bar are carried, and the rotary turret 12, in which the looper mechanism is carried, are rotated in unison during the sewing about the eye of the button-hole through shafts 38 geared to the head and turret, and operated by connected gear segments 40, one of which is provided with an arm carrying a roll engaged by a cam on the main cam-shaft of the machine.
- 10 In embodying the present invention in the machine above described, a rotary take-up mechanism for taking up and controlling the upper needle thread is combined with the stitch-forming mechanism, and this 15 take-up is preferably arranged above the needle bar so that the thread may lead from the take-up directly to the upper end of the bar. The term "rotary take-up" is used herein to define a take-up which rotates in 20 the same direction in taking up and giving out the thread, as distinguished from oscillating take-ups which move in opposite directions in taking up and giving out the thread. As shown, the take-up comprises 25 two disks 42, which are spaced to provide a thread-guiding passage between them and are connected by a screw-stud 44 which also acts as a take-up crank pin for engaging and operating upon the upper needle thread.
- 30 The disks are also connected by a second screw-stud 46 which is arranged substantially in the axis of the take-up. This central stud may be, and preferably is, arranged slightly eccentric to the axis of the 35 take-up so that it will modify the action of the take-up pin 44 as it begins to take up the needle thread during the upward stroke of the needle and as it ceases to act upon the thread during the downward stroke of the 40 needle. The inner disk 42 of the take-up is secured to or formed on the end of the needle-driving crank pin 32, so that the take-up is secured to and rotates with the needle shaft. The thread leads from the 45 eye of the needle, through a light tension device 48 mounted on the side of the needle bar, up through the hollow needle bar, over the take-up pin 44, from which it leads under a thread guide 50 to a tension device 52, 50 and thence through suitable guides to the thread supply.

With the above construction and arrangement the needle thread is smoothly and uniformly taken up and controlled without complication of the parts and without sudden or violent strains or pulls on the thread.

While it is preferred to employ the specific construction and arrangement of parts shown and described, especially in embodying the invention in the machine of the application above referred to, it will be understood that this construction and arrangement is not essential to the broader features of the invention, but may be varied or modi-

fied as found desirable or best suited to the 65 construction and arrangement of the parts and mechanisms of the machine in which it is to be embodied.

Having explained the nature and object of the invention, and specifically described 70 one form of mechanism in which it may be embodied, what is claimed is:

1. A sewing machine, having, in combination, a work clamp, a stitch-forming mechanism comprising an upper needle bar 75 and needle and a complementary under thread mechanism, rotary supports in which the stitch-forming mechanism is mounted, a rotary take-up acting on the upper needle thread adjacent to the needle bar, and mechanism for relatively actuating the stitch-forming mechanism and work clamp to sew about a buttonhole.

2. A sewing machine, having, in combination, a work clamp, a stitch-forming 85 mechanism comprising a vertically-reciprocating hollow needle bar and a complementary under thread mechanism, a rotary take-up above the needle bar from which the thread leads directly into the bar, and mechanism for relatively actuating the stitch-forming mechanism and the work clamp to 90 sew about a buttonhole.

3. A sewing machine, having, in combination, a stitch-forming mechanism comprising a vertically-reciprocating upper 95 needle bar, a rotary support for the bar, and a rotary take-up acting on the needle thread above the needle bar.

4. A sewing machine, having, in combination, a stitch-forming mechanism comprising a vertically-reciprocating hollow needle bar, and a rotary take-up above the 100 bar from which the thread leads directly into the bar.

5. A sewing machine, having, in combination, a stitch-forming mechanism comprising a vertically-reciprocating upper needle bar, a crank for reciprocating the bar, a take-up secured to the crank above 110 the needle bar and provided with a take-up crank stud.

6. A sewing machine, having, in combination, a stitch-forming mechanism comprising a vertically-reciprocating and laterally-vibrating needle bar and a complementary under thread mechanism, and a rotary take-up for the needle thread arranged above the needle bar.

7. A sewing machine, having, in combination, a stitch-forming mechanism comprising a vertically-reciprocating needle bar, a crank for reciprocating the bar, take-up disks secured to the crank above the needle bar, a take-up crank pin between the 125 disks, and a substantially central pin between the disks.

GEORGE S. HILL.
